GUN FIRING MECHANISM

Bryan P. Joyce, East Orange, N. J., assignor to
American Armament Corporation, New York,
N. Y., a corporation of New York

Application September 19, 1935, Serial No. 41,317

12 Claims. (Cl. 89—27)

This application is a continuation in part of my parent U. S. application Serial No. 754,150, filed November 21, 1934.

The invention relates to a gun designed primarily for use upon aircraft and it aims to provide a new and improved firing mechanism allowing either automatic or manual operation of the gun and capable also of preventing firing when desired.

10 The gun is of a type in which a slidable breech block is moved to closed position under the influence of a spring, and in which the closing of said breech block swings a sear lever to cock a firing pin, and further objects are to provide 15 novel means to prevent any rebound of the breech block under the influence of the firing pin spring after said breech block closes, and to make novel provision whereby the firing mechanism is locked against action until said breech 20 block is fully closed.

With the foregoing and other objects in view which may become apparent as description proceeds, the invention resides in the novel subject matter hereinafter described and claimed, description being accomplished by reference to the 25 accompanying drawings.

Fig. 1 is a perspective view illustrating the general arrangement of parts and showing the gunner in the gunner's basket in readiness for action.

30 Fig. 2 is a side elevation partly broken away and in section.

Fig. 3 is a vertical longitudinal sectional view partly broken away showing the parts in position for firing, herein referred to as battery position.

35 Fig. 4 is a front elevation.

Fig. 5 is a fragmentary longitudinal sectional view partly in elevation illustrating primarily parts of the firing and magazine mechanisms and parts of the actuating means for the rotary spider which feeds the rounds from the magazine.

40 Fig. 6 is a vertical transverse sectional view substantially on line 6—6 of Fig. 5.

45 Fig. 7 is a vertical sectional view partly in elevation showing the breech block lowered and illustrating the manner in which the empty shell cases ejected from the gun are deflected into a receiver.

50 Fig. 8 is a fragmentary side elevation showing part of the actuating mechanism for the firing means.

Fig. 9 is a vertical transverse sectional view on line 9—9 of Fig. 8.

55 Fig. 10 is a fragmentary side elevation showing parts of the mechanism for actuating and controlling the firing means, viewed as indicated by the arrow 10 of Fig. 9.

Fig. 11 is a bottom plan view of a number of 60 the parts shown in Fig. 8.

Fig. 12 is a perspective view illustrating the principal parts of the mechanism for actuating and controlling the firing means.

Fig. 13 is a top plan view.

Fig. 14 is a view similar to Fig. 3 but partly in elevation illustrating the relation of parts as counter-recoil terminates.

Fig. 15 is a perspective view showing the mechanism for cocking the firing pin and locking it in cocked position.

10 Fig. 16 is a view similar to Fig. 15 but showing the firing pin released.

Fig. 17 is an enlarged longitudinal section partly in elevation showing parts of the mechanism which trips the firing mechanism, showing 15 said tripping mechanism in the locked position which it occupies from the time the breech block opens until it fully closes.

Fig. 18 is a view similar to Fig. 17 but showing the tripping mechanism for the firing mechanism released in readiness to permit firing.

Fig. 19 is a view similar to Figs. 17 and 18 but showing the relation of parts when firing is effected.

Figs. 20 and 21 are transverse sectional views 25 on lines 20—20 of Fig. 19 and 21—21 of Fig. 17, respectively.

Fig. 22 is a top plan view of the piston which forms part of the breech block closing means and carries a cam for actuating the locking 30 means of the mechanism which trips the firing mechanism.

Figs. 23 and 24 are side elevations of the locking rod for the aforesaid tripping mechanism.

The specific construction shown in the drawings will be definitely described with the understanding, however, that within the scope of the invention as claimed, numerous variations may be made, the disclosure being illustrative rather than limiting.

40 I have shown an annular track 50 (Fig. 2) to be secured to an aircraft (not shown) around the edge of a cockpit. Partly overlying and partly within and concentric with the track 50, is a ring 51 from which pipes or other structural 45 members 52 project downwardly, the lower ends of said members 52 being connected by other pipes or structural members 53 so that the ring 51 and the various structural members 52, 53 cooperate in forming a gunner's basket in which 50 an adjustable seat 54 may be provided for the gunner.

Two gun-mounting side frames 59 span the ring 51 and are secured thereto, and the gun is supported on these side frames by trunnions 60 55 so that said gun may be elevated or depressed as required. A hand wheel 61 is provided to effect turning of the gun about the trunnions 60. The hand-wheel 61 is operated by the gunner's left hand, and rigid hand grips 67 are shown pro- 60

jecting outwardly from the track 50 to be engaged by his right hand, so that by pushing or pulling on these hand grips, the gunner may rotate the entire basket and the gun to traverse the latter, said hand grips 67 being shown only in Fig. 1.

A brake 68 (Fig. 13) is carried by the basket to engage the track 50, and a cable 76 depends from said brake to a brake pedal 77 (Figs. 1 and 10 13) mounted in the lower end of the gunner's basket in position to be engaged by his right foot. A supporting plate 78 may be provided for the left foot as shown in Figs. 1 and 13, but when the gun is being operated, this foot engages a firing pedal 79 which is mounted in the gunner's basket and is connected with the lower end of a cable 80, the upper end of this cable being connected with a mechanism hereinafter described for effecting either single shot 15 operation of the gun or automatic operation.

The gun is of a type to receive the rounds shown at 82 in a number of the views, from a clip 83 within a magazine 84. The rounds 82 fed from the magazine 84 are automatically loaded into the gun by a loading tray 160 and a loading plunger 161, and upon counter-recoil, the empty shell cases 85 are rearwardly ejected into a receiver 86.

The trunnions 60 above described support a 30 cradle shown at 104 in a number of the main views, and the gun barrel 105 is slidably mounted in said cradle in any preferred way so that it may recoil and counter-recoil. A recoil check is shown at 106 and a counter-recoil spring at 107, 35 and appropriate counter-poise mechanism is illustrated in a general way at 108.

The gun barrel 105 is provided with a vertically slidable breech block 109 carrying a conventional firing pin 110 and its spring 110^a, and 40 a bell crank or sear lever 111 connected with said pin. Suitable ejectors 112 are provided to eject the shell cases 85 when the breech block 109 lowers upon counter-recoil of the barrel 105, said ejectors serving also to hold said breech block in lowered position until the next round is 45 loaded into the gun breech. For operating the ejectors 112 and for causing them to temporarily lock the breech block 109 lowered, studs 113 are provided on the ejectors mounted in slots 114 in the breech portion of the gun and operable in grooves 115 in the sides of the breech block (see Fig. 7). I have not gone into any particular detail with regard to these structural features, for they are known.

55 The rear portion of the gun barrel carries a transverse rock shaft 116 having an arm 117 connected with the breech block 109, for lowering and raising said breech block, one end of said shaft 116 being preferably squared as seen 60 in Fig. 5 to be engaged by a hand crank or the like, if desired. The other end of shaft 116 is provided with an operating arm 118 (Figs. 5 and 6) which is cooperable with a known one-way dog 119 (Figs. 5 and 6) to lower the breech 65 block 109 after recoil has occurred and counter-recoil has started. Upon recoil of the gun barrel, the arm 118 merely swings the dog 119 out of its way as shown in dotted lines in Fig. 5 but upon counter-recoil, dog 119 operates arm 118 to turn shaft 116 and lower the breech block. When this 70 occurs, the ejectors 112 eject the empty shell case 85 and then serve to hold the breech block lowered until a new round is inserted.

Suitably connected with the shaft 116 is the 75 chain of an assemblage of chain 120, piston 121,

and spring 122. When the breech block 109 lowers, the chain 120 is pulled, causing movement of the piston 121 to compress the spring 122. As soon as the breech block is released by insertion of a round into the gun barrel, spring 5 122 expands and moves piston 121 and chain 120 to again raise the breech block. During this raising, the sear lever 111 coacts with a nose 10 123 on a trigger shaft 124 to retract the firing pin 110 against the action of spring 110^a as shown in Fig. 3, said firing pin and sear lever being held cocked by a spring pressed latch pin 110^b mounted in the breech block 109 to prevent said spring from causing rebound of said breech block when the latter reaches closed 15 position. If the gun be set for manual control as hereinafter described, the firing pin 110 will remain retracted until the gunner depresses the firing pedal 79 but if the gun be set for automatic operation, said firing pin will be released 20 as soon as the breech block 109 is entirely closed. The trigger shaft 124 is provided with a releasing cam 110^c for latch pin 110^b, and is provided on one end with a firing trigger 125 which is in the rearward path of an arm 126 (Fig. 5), said arm 126 being loosely pivoted at 127 to the left side of the breech portion of the gun barrel. The rear end of a longitudinally extending rod 128 abuts the arm 126 (see Figs. 5, 9, 10 and 12), 30 said rod 128 extending forwardly through a suitable guiding casing 129 and being provided with a spring 130, said spring being operable to rearwardly force said rod 128 to effect firing of the gun, after said rod is forwardly forced to compress spring 130 and then released. 35

The lower end of arm 126 is bifurcated and straddles a rotatable and slidable locking rod 126^a which is mounted in bearings 126^b and 126^c at the front and rear ends of the cylinder 121^a which guides the piston 121, said rod 126^a being disposed over said cylinder. This rod 126^a is provided with a collar 126^d to abut the rear edge of the arm 126 for swinging said arm 126 forwardly to forwardly slide rod 128 and compress spring 130 when said rod 126^a is forwardly slid, and this forward sliding of rod 126^a is effected by a lug 126^e on piston 121 when this piston is pulled forwardly upon lowering of the breech block 109, during counter-recoil. When counter-recoil has almost been completed, arm 126 contacts with rod 128 45 50 forcing it forwardly and compressing spring 130. If the gun be set for manual operation, the rod 128 will remain in its forward position due to the latching means hereinafter described, but if the gun be set for automatic operation, just as soon as the breech block closes, spring 130 actuates the rod 128, causing the arm 126 and trigger arm 125 to turn trigger shaft 124, releasing the sear lever latch pin 110^b and the sear lever 111 to release the firing pin 110. 55 60

Until the breech block fully closes, the rod 126^a locks the arm 126 against rearward movement, due to construction now to be described (see more particularly Figs. 17 to 21), and therefore, the gun cannot be prematurely fired. The front end 65 of rod 126^a is provided with two longitudinal ribs 126^f slidable in grooves 126^g in the bearing 126^b and when said rod 126^a reaches its foremost position, said ribs 126^f are clear of said grooves 126^g. A cam 126^h on the piston lug 126^e then turns a 70 cam 126ⁱ on collar 126^d and turns rod 126^a to dispose the ribs 126^f out of alignment with the grooves 126^g. These ribs and the bearing 126^b then prevent rod 126^a from sliding rearwardly, and the gun cannot, therefore, fire until said 75

ribs are released from said bearing. This is accomplished when the breech block 109 closes, by means of a second cam 126^b on the piston lug 126^c and a cam 126^c on the rod 126^a. As piston 121 completes its breech-block-closing movement, its cam 126^b engages cam 126^c and turns rod 126^a until the ribs 126^c are in alignment with the grooves 126^b. The rod 126^a is then free to slide rearwardly and the gun can consequently be fired by rod 128 swinging arm 126 against the firing trigger 125.

A latch 134 (Figs. 2, 9, 10 and 12) is provided for coaction with the rod 128 to hold the latter against movement under the influence of the spring 130 after said rod has been forwardly moved to compress said spring, but this latch 134 is permitted to function only if the gun is being manually instead of automatically fired. If manual firing is to be effected, the latch 134 is allowed to hold the rod 128 in the forward position shown in Figs. 10 and 12, until firing is to be accomplished. Then, the release of latch 134 will allow rod 128 to move rearwardly under the influence of the spring 130, tripping the firing mechanism as above explained. If the gun is being automatically operated, the latch 134 is held in released position so that after each forward movement and release of rod 128, spring 130 will rearwardly slide said rod as soon as the breech block 109 closes.

In the present showing, the latch 134 is in the form of an inverted L pivotally mounted at 135 upon the portion 136 of the cradle which contains the counter-recoil spring 107, and the horizontal arm of said latch is cooperable with a downwardly projecting stud 137 on the front end of rod 128. The vertical arm of the latch 134 is pivotally connected at 138 with a shaft 139 (Figs. 8, 9, 10 and 12), said shaft passing rotatably through a portion of the cradle and being also slidably. Pulling the shaft 139 in one direction releases the latch 134 and compresses a spring 140 which surrounds said shaft. A slidable member 141 connected with the cable 80 above described, is provided for pulling the shaft 139 in latch-releasing direction and then releasing said shaft if manual firing is to be effected, or for pulling said shaft to latch-releasing position and holding it in this position if automatic firing is to be carried out. The member 141 is shown more particularly in Figs. 8, 11 and 12 and this member is cooperable with a short lug 142 or a long lug 143 on the shaft 139. The member 141 is provided with one cam portion 144 for coaction with the lug 142 when manual firing is to be effected, and is provided with another cam portion 145 for coaction with the long lug 143 when the gun is to fire automatically, and the shaft 139 may be turned by means of a crank 146 to dispose either of said lugs in operative relation with the member 141 or to so locate said lugs that neither one of them can be engaged by said member 141. A latch pin 147 is slidably in the handle of the crank 146 and is releasable by a knob 148, said latch pin being cooperable with three sockets 149 in the adjacent portion of the gun cradle (Fig. 10). The latch pin may thus be used for holding the shaft 139 in any one of its three positions. When said shaft is set as shown in Figs. 8 and 9, each time the member 141 is pulled by the cable 80, the cam portion 144 engages the short lug 142, pulling the shaft 139 to release the latch 134, allowing firing of the gun, and just as soon as the latch has been released, said cam portion 144 releases the lug 142 and spring 140 returns said

shaft 139, so that latch 134 is in readiness to again hold rod 128 when this rod is again forced forwardly. For manual firing, the operator of course releases the foot pedal 79 after the shot has been fired, whereupon a spring device 150 returns the member 141 to its normal position.

When the shaft 139 is turned to place the long lug 143 in operative relation with the cam portion 145 of the member 141, the gunner will depress the foot pedal 79 and hold it depressed. This causes the cam portion 145 of member 141 to engage lug 143, slide shaft 139 to release latch 134 and hold this latch in released position so that rod 128 may rearwardly return each time it is forced forwardly, thus effecting automatic firing. When shaft 139 is set in a neutral position, operation of member 141 cannot effect movement of said shaft.

The member 141 is preferably of the L-shape shown in Fig. 11, being bifurcated to straddle a fixed track 151 which is suitably secured to the gun cradle, said track 151 having a longitudinal slot 152 which receives a pin 153 carried by the member 141. This member 141 is thus effectively guided and is allowed a tilting movement as shown in dotted lines in Fig. 11. This tilting movement is necessary in order to allow member 141 to pass the end of shaft 139 carrying the lugs 142 and 143 as member 141 is returned to its normal position by the spring device 150, said member 141 then clicking idly over said lug 142.

A pivotally supported lock 154 is shown, capable of positively locking the rod 128 in gun-cocked position, said lock being suspended from a shaft 156 controlled by a feeler 159 in the magazine 84 to prevent firing of the last round in the gun before placing a new clip of rounds in said magazine. If the last round from the magazine were fired after insertion into the barrel breech, further automatic operation could not be effected upon insertion of a new clip, without first loading the gun by hand. Such hand loading, however, is not required by leaving one unfired round in the gun, as above described.

When the gun has been automatically operating and the last round is loaded into it, the gunner of course releases the foot pedal 79 before inserting a new clip of rounds into the magazine 84. This insures that by the time the lock 154 is released, latch 134 will be in position to hold the rod 128 against movement in gun-firing direction. Otherwise, the rod 128 would effect gun firing immediately upon insertion of a new clip and consequent release of lock 154.

While the operation of the structure as a whole would probably be understood from explanations hereinbefore given in connection with the various groups of coacting elements, it may be briefly explained as follows:—The initial round is, of course, inserted by hand by manually lowering the breech block 109 with a crank or the like applied to the squared end of the shaft 116. Lowering the breech block pulls upon chain 120, compressing spring 122 and moving piston 121 (see Fig. 5) forwardly. During the forward movement of piston 121, its cam 126^b pushes against the cam 126^c of rod 126^a, this rod being now held against rotation by the ribs 126^c in the grooves 126^b so that said rod is slid forwardly, causing its collar 126^d to forwardly swing the arm 126, forwardly sliding the rod 128 and compressing the spring 130, so that the entire tripping means for the firing means (125, 124, 123, 111, 110, 110^a) is set in readiness for action. As soon as this is accomplished, the ribs 126^c clear

the grooves 126^e and the rod 126^a is turned under the influence of the cams 126^h and 126ⁱ to dispose said ribs 126^f out of alignment with said grooves, prohibiting the rearward movement of said rod 126^a and arm 126 necessary to trip the trigger arm 125 and fire the round, until the rod 126^a is released. This release is effected only when the breech block 109 closes as will be more fully explained. We will now assume that the 5 crank 146 (Figs. 10 and 12) has been moved upwardly and forwardly to the "one shot" position so that the latch 134 will engage the rod 128 in its forward gun-cocked position. After inserting the first 10 round by hand, the breech block is allowed to close under the influence of the spring 122 and as said breech block closes, the sear lever 111 and finger 123 coact to retract the firing pin 110, and the latch pin 110^b engages said sear lever to hold it retracted as seen in Figs. 3 and 15. The 15 rearward movement of piston 121 incident to breech-block-closing, causes the cams 126^j and 126^k to turn rod 126^a to realine the ribs 126^f with the grooves 126^e, said cams then pushing said rod 126^a rearwardly to move collar 126^d away 20 from arm 126, so that this arm may be rearwardly swung by rod 128 when latch 134 is released. Depression of the firing pedal 79 will now pull cable 80 and actuate the member 141 to pull the shaft 139 in a direction to release the 25 latch 134, allowing rod 128 to slide rearwardly under the influence of spring 130, rocking shaft 124 to release the latch pin 110^b and trip the firing pin 110 to fire the round. It is to be recalled that at this time, the lock 154 is held in 30 released position by one of the rounds in the magazine contacting with the feeler 159, so that said lock will not interfere with rearward sliding of the rod 128. As soon as the round is fired, recoil of the barrel occurs, and then counter-recoil, these movements serving to actuate the shell-ejecting and barrel-reloading mechanism.

If the crank 146 be set for automatic operation, the gunner depresses the firing pedal 79 45 and holds it depressed so that the member 141 will hold the shaft 139 and in turn hold the latch 134 in released position. With this latch so held, it cannot hold the rod 128 the next time the latter is forced forwardly by arm 126. Consequently, just as soon as the breech block is closed after the automatic loading of the round into the breech, the rod 128 will be slid rearwardly by the spring 130 causing arm 126 to strike the firing trigger 125, releasing the firing 50 pin 110 and firing the round. The gun will now operate automatically as long as the firing pedal 79 is held depressed until the last round from the magazine 84 has been loaded into the breech. When this has occurred, however, the lock 154 55 automatically prevents firing of this last round until the magazine is reloaded.

Whenever desired, the crank 146 may be set in its neutral or safe position so that any movement which may be imparted to the member 141 by the firing pedal 79, will not cause firing of the gun.

Attention is again invited to the possibility of making numerous variations within the scope of the invention as claimed.

70 I claim:—

1. In an automatic gun having an automatically actuated breech block, and automatically cocked firing means having a firing trigger; tripping means for said firing trigger self-actuated 75 when forced in one direction and released, and

means operatively connected with said breech block and said tripping means for forcing the latter in said one direction when said breech block is opened and for releasing said tripping means when said breech block is closed. 5

2. In an automatic gun having a breech block, automatic actuating means for said breech block including an assemblage of spring, pull chain and piston for closing said breech block, the chain and piston being movable by opening of the breech block to store energy in said spring, and automatically cocked firing means having a firing trigger; tripping means for said firing trigger self-actuating when shifted in one direction and released, said piston and said tripping 10 means having coacting portions for shifting said tripping means in said one direction when the breech block is opened and for releasing said tripping means when said breech block is closed. 15

3. In an automatic gun having an automatically actuated breech block, and automatically cocked firing means having a firing trigger; tripping means for said firing trigger self-actuating when forced in one direction and then released, means operatively connected with said breech 20 block and said tripping means for forcing the latter in said one direction each time said breech block is opened and for freeing said tripping means each time said breech block is closed, latch means for latching said tripping means when moved in said one direction if the gun is to be held in cocked position, manually operable releasing means for said latch means embodying means adjustable to one position at which said releasing means will release said latch and then allow 25 return of the latter to operative position, to a second position at which said releasing means will hold said latch means in released position 30 for automatic gun operation, and to a third position at which said releasing means cannot release said latch means. 35

4. In an automatic gun having a member which is forced in one direction and is then self-shifting in the other direction to effect gun firing; a latch engageable with said member to hold the gun in cocked position, a self-returning rod connected with said latch for releasing it, means mounting said rod for rotation and sliding, a relatively short lateral lug and a relatively long lateral lug on said rod, a movably mounted manually operable member for moving said rod in latch-releasing direction, said member having a cam portion for coaction with said short lug to move said rod and then release it, and having another cam portion cooperable with said long 50 lug for moving said rod to released position and holding it in said released position, and means for rotating said rod to one position at which said short lug and its respective cam portion will coact, to a second position at which said long lug and its respective cam will coact, and to a third position at which neither lug will be engaged by either cam portion. 55

5. In an automatic gun having a breech block, automatic actuating means for said breech block including an assemblage of spring, pull chain and piston for closing said breech block, the chain and piston being movable by opening of the breech block to store energy in said spring, and automatically cocked firing means having a firing trigger; tripping means for said firing trigger cooperatively related with said piston and shiftable to a set position by movement of said piston in breech-block-opening-direction, and means cooperatively related with said piston and 70

- releasable by movement of said piston to breech-block-closing-position for holding said tripping means in said set position until the breech block closes.
- 5 6. In an automatic gun having a breech block, automatic actuating means for said breech block including an assemblage of spring, pull chain and piston for closing said breech block, the chain and piston being movable by opening of the breech block to store energy in said spring, and automatically cocked firing means having a firing trigger; tripping means for said firing trigger cooperatively related with said piston and shiftable to a set position by movement of said piston in breech-block-opening-direction, and means cooperatively related with said piston, applied by the movement of said piston in said breech-block-opening-direction and released by movement of said piston to breech-block-closing-position for holding said tripping means in said set position until the breech block closes.
7. In an automatic gun having a breech block, automatic actuating means for said breech block including an assemblage of spring, pull chain and piston for closing said breech block, the chain and piston being movable by opening of the breech block to store energy in said spring, and automatically cocked firing means; tripping means for said firing means including a member movable substantially uni-directionally with said piston, a slidable and rotatable rod mounted parallel with the line of travel of said piston, said rod having a shoulder positioned to abut said member and move it to a set position in readiness for action, coacting means on said piston and rod for sliding said rod to a predetermined position when said piston moves in breech-block-opening-direction to set said member and for then turning said rod, means applied by said turning of said rod for holding the rod in said predetermined position, and coacting means on said piston and rod for reversely turning said rod to release said holding means therefor when said piston moves to breech-block-closing-position.
8. In an automatic gun having a breech block, automatic actuating means for said breech block including an assemblage of spring, pull chain and piston for closing said breech block, the chain and piston being movable by opening of the breech block to store energy in said spring, and automatically cocked firing means; tripping means for said firing means including a member movable substantially uni-directionally with said piston, a slidable and rotatable rod mounted parallel with the line of travel of said piston, said rod having a shoulder positioned to abut said member and move it to a set position in readiness for action, a bearing in which said rod is slidable and rotatable, said bearing being provided with a groove and said rod with a rib which slides in said groove until said rod reaches a position at which said member is in said set position in readiness for action, said rib then clearing said groove, coacting means on said piston and rod for sliding the rod to said position as said piston moves in breech-block-opening-direction and for then turning said rod to cause said rib to abut said bearing and temporarily hold said rod and said member against return, and coacting means on said piston and said rod for reversely turning the latter to again align said rib with said groove as
- said piston reaches breech-block-closed-position.
9. In a gun having a breech block carried by the breech portion of the gun barrel, opening and closing means for said breech block, a spring-actuated firing pin mounted in said breech block, a sear lever fulcrumed in said breech block and so connected with said firing pin that the latter may be cocked by swinging said sear lever, and a trigger shaft mounted on said breech portion of the gun barrel independently of the breech block and having a trigger portion to abut said sear lever and swing the same to cock said firing pin as the breech block closes; a self-applied latch mounted in said breech block in position to engage said sear lever and hold it in firing pin-cocked-position, and means actuated by said trigger shaft for releasing said latch when said trigger shaft is turned to release said trigger portion from said sear lever.
10. In a gun having a breech block carried by the breech portion of the gun barrel, opening and closing means for said breech block, a spring-actuated firing pin mounted in said breech block, a sear lever fulcrumed in said breech block and so connected with said firing pin that the latter may be cocked by swinging said sear lever, and a trigger shaft mounted on said breech portion of the gun barrel independently of the breech block and having a trigger portion to abut said sear lever and swing the same to cock said firing pin as the breech block closes; a self-applied latch mounted in said breech block in position to engage said sear lever and hold it in firing-pin-cocked-position, and a cam on said trigger shaft engaging a portion of said latch for releasing said latch when said trigger shaft is turned to release said trigger portion from said sear lever.
11. In an automatic gun, a barrel, an automatically actuated breech block therefor, automatically cocked firing means having a firing trigger mounted on said barrel independently of said breech block, tripping means for said firing trigger mounted on said barrel and including an actuating spring, said trigger tripping means being effective to stress said actuating spring for operation when said trigger tripping means is moved in a predetermined manner, and operating connections between said breech block and said trigger tripping means for moving the latter in said predetermined manner as the breech block opens and for releasing said trigger tripping means upon breech block closing, allowing the stressed spring to actuate said trigger tripping means to fire the gun.
12. In an automatic gun, a barrel, an automatically actuated breech block therefor, automatically cocked firing means having a firing trigger mounted on said barrel independently of said breech block, tripping means for said firing trigger mounted on said barrel and including a longitudinally extending slidable rod and an actuating spring surrounding said rod, said rod being effective to stress said actuating spring for operation when said rod is slid forwardly, and operating connections between said breech block and said trigger tripping means for so moving the latter as to forwardly slide said rod as the breech block opens and for releasing said trigger tripping means upon breech block closing, allowing the stressed spring to actuate said trigger tripping means to fire the gun.

BRYAN P. JOYCE.
